UNITED STATES PATENT OFFICE.

FRANK J. MINER, OF DETROIT, MICHIGAN.

BEARING-WHEEL.

1,239,288.

Specification of Letters Patent. Patented Sept. 4, 1917.

Application filed May 21, 1917. Serial No. 169,860.

To all whom it may concern:

Be it known that I, FRANK J. MINER, a citizen of the United States of America, residing at Detroit, in the county of Wayne 5 and State of Michigan, have invented certain new and useful Improvements in Bearing-Wheels, of which the following is a specification, reference being had therein to the accompanying drawings.

10. This invention relates to a bearing wheel for heavy service vehicles, particularly automobile trucks, tractors or the like, of a type wherein an articulated periphery of suitable segments is brought under load in 15 such manner as always to impose a comparatively large bearing tread upon the ground. One of the features of the invention is that the method of transmission of weight is such that the friction on the pivot bearing 20 of the device is minimized, the load being carried almost entirely by a comparatively large roller and spacing devices, while side strain is taken care of in such a manner as to insure the durability of the device even 25 under exceptionally hard service.

The invention consists in the matters hereinafter set forth, and more particularly pointed out in the appended claims.

Referring to the drawings,

30. Figure 1 is a view in side elevation, partially broken away and in section, of a bearing wheel that embodies features of the invention;

Fig. 2 is a view in plan of the wheel, likewise partially broken away and in section; and

Fig. 3 is in transverse section, the parts being shown in elevation, of the device.

As herein indicated, a continuous track 40 of elongated oval shape with flat sides is afforded by a suitably disposed central track plate 1, through which a main shaft or bearing axle 2 extends, there being a suitable hub 3, the proportion of the axle and hub 45 being modified, to meet different requirements of service, and being indicated herein merely diagrammatically.

A series of tread sections 4 that are recessed to act as housings for spacing rollers 5, encircle the track, being linked together by intermediate sections 6, the end portions of which overlap the segments 4 and are pivotally connected thereto by the bearing pins or pivots 8 on which the rollers 5 are 55 centered.

The relation and proportions of the seg-

ments 4 and 6 and the diameters of the spacing rollers 5 are such that the latter are always in rolling contact with the track plate periphery while the segments present 60 the successive tread faces thereof to the ground as the device advances. It is to be understood that the rollers or spacing wheels 5 may have trunnion bearings in the block and that other details of good mechanical 65 construction may be employed to minimize friction.

In order to avoid the entrance of dirt into the device and make the same self cleaning, the segments 4 are so recessed to receive 70 the rollers that the end flanges 9 thereof which envelop the rollers continue well around the same the flanges being in substantially sliding engagement with filler blocks 10 interposed between the sides of 75 the sections. These filler blocks back up the tread portions of the links 6 which connect the blocks or segments 4.

It is to be understood that where the link sections are comparatively short and there are a great number of segments as where the track is greatly elongated to carry a heavy load, that the filler blocks between the segments in the links may be omitted, and the links themselves may be narrowed, 80 so as not to tread upon the ground, but in ordinary construction the arrangement herein shown is preferable. In order to house the track and interior portions the plate 11 and cover 12 may be secured to the track 90 plate 1 as by strids 13 passing through suitable boxes or lugs 14 of the track.

Where it is desired to make the wheel a traction wheel as well as a bearing wheel, provision may be made for driving it as for 95 example, by a link rack 15 the segments of which are pivoted to the pins connecting the segments and links, engaging a suitable drive gear 16 upon the main shaft. Or any other preferred form of driving means may be 100 employed.

It is further to be understood that the width and proportion generally of the segments and links may be varied to obtain the necessary tread surface, and that they may 105 be duplicated upon the same shaft.

As a result of this construction, a bearing wheel is obtained in which the tread surface does not progress upon the ground, but the load is carried upon a track which passes 110 over rollers that are successively laid as the segments and links fall into position and

thereby eliminate to a large extent the friction which is common in ordinary wheels of this character. The entire load is transmitted to the body of the roller and as they can be made of quite large diameter, the friction is largely eliminated.

Obviously, changes in the details of construction may be made and I do not care to limit myself to any particular form or arrangement of parts.

What I claim is:—

1. A bearing wheel for vehicles comprising a track plate, segments having recessed end portions pivoted together in overlapping relation to form an endless tread member encircling the track plate, and spacing wheels mounted in the recesses of the overlapping portions of the segments in rolling contact with the track plate margin.
2. A bearing wheel for vehicles comprising a track plate, segments having recessed end portions pivoted together in overlapping relation to form an endless link tread member encircling the track plate, spacing wheels mounted in the recesses of the overlapping portions of the segments in axial coincidence with the pivots thereof and in rolling contact with the track plate margin, and dust guards on the segments filling the intervals between the ends of the segments.
3. A bearing wheel for vehicles comprising a track plate, oppositely disposed segments having recessed end portions pivoted together in overlapping relation to form an endless link tread member encircling said

track plate, spacing wheels mounted in the recesses of the segments in axial coincidence with the pivots thereof and in rolling contact with the track plate, and side plates carried by the track plate and housing the latter and adjacent portions of the segments.

4. A bearing wheel for vehicles comprising a track plate, oppositely disposed segments having recessed end portions pivoted together in overlapping relation to form an endless tread member encircling the track plate, spacing wheels in the recesses of the segments at the pivotal points thereof in rolling contact with the track plate, rack links articulating on the pivotal connections of the segments, and a driving gear meshing with the rack links, in concentric relation with the tread member.

5. A bearing wheel comprising a track plate, a set of segments having recessed end portions, a set of segments alternating therewith and having recessed end portions pivoted to the other end portions in overlapping relation thereto, and spacing wheels journaled in the recesses of the segments in axial coincidence with the pivots thereof and in rolling contact with the periphery of the track plate which the articulated segments encircle.

In testimony whereof I affix my signature in the presence of two witnesses.

FRANK J. MINER.
